UNITED STATES PATENT OFFICE.

FRANK A. LUNDQUIST, OF NEW YORK, N. Y., ASSIGNOR TO WESTERN ELECTRIC COMPANY, INCORPORATED, OF NEW YORK, N. Y., A CORPORATION OF NEW YORK.

AUTOMATIC SELECTING-SWITCH.

1,287,715.

Specification of Letters Patent. Patented Dec. 17, 1918.

Application filed November 27, 1916. Serial No. 133,611.

To all whom it may concern:

Be it known that I, FRANK A. LUNDQUIST, a citizen of the United States, residing at New York, in the county of New York and State of New York, have invented certain new and useful Improvements in Automatic Selecting-Switches, of which the following is a full, clear, concise, and exact description.

10 This invention relates to switching apparatus for use in telephone exchange systems, and more particularly to power driven panel switches of the multi-brush type, that is, switches of the type provided with a plurality of brush sets, any one of which may be rendered operative in extending a call. More specifically this invention relates to improvements in the operating mechanism of such a switch, and generally stated, its 20 object is to provide for the direct control of such a switch through trains of impulses transmitted from a standard substation impulse-transmitting device.

The principal feature of this invention is 25 the provision of means for causing a power driven switch to be responsive to impulses transmitted directly from an impulser rather than to impulses transmitted from the switch itself, and controlled by a sender of 30 any well-known type.

According to this feature, the selection of the stationary terminals of the desired line is effected by the sending of a train of impulses to activate one of a plurality of sets 35 of brushes having access to a corresponding plurality of major groups of terminals, the sending of a second train of impulses to direct the selection of a plurality of like levels in a corresponding plurality of minor groups, and the sending of a third train of 40 impulses to direct the selection of a particular set of terminals within a minor group of said terminals and located at the preselected level.

45 The selection of the particular set of brushes is accomplished in response to a first set of impulses through a trip rod of well-known type, and the actuation of the switch in response to the second and third sets of 50 impulses is accomplished through a step-by-step vertical, and a step-by-step rotary movement of an auxiliary shaft or trip rod whereby a particular finger at a particular level is positioned before a stop on the 55 brush rod of such a switch. The first set

of impulses having been received and the brush-tripping rod having been properly positioned, a second set of impulses is transmitted, and results, first, in the tripping of the selected set of brushes, and, second, in 60 the movement of the auxiliary shaft downward to select a plurality of levels each of which corresponds to the second set of impulses. Upon the transmission of a third set of impulses the auxiliary shaft is rotated 65 to select one of the previously selected plurality of levels by positioning a particular finger thereon in correct relation to the brush carriage to stop the brush before the desired set of terminals at the selected level. 70 At the same time means are actuated for driving the brush carriage downward under a source of mechanical power. When the brush carriage reaches the position limited by the selected finger of the auxiliary trip 75 rod, the source of mechanical power for driving the brush carriage downward is disengaged, and the selected brushes come to rest upon the selected set of terminals.

An added feature of this invention lies 80 in the arrangement of the terminals in the contact banks. The contact bank, as a whole, is divided into a plurality of major groups of one hundred sets of terminals each. Each major group is further sub- 85 divided into ten minor groups whose terminals are designated by two digits, a tens digit and a units digit. All terminal sets in a minor group are designated by the same units digit and by the ten different tens digits in proper order. The arrangement within the major group then is such that corresponding terminal sets in the ten minor groups are designated by the same tens digits and a different one of the ten units 90 digits in the proper order. The selection of a particular set of terminals then is accomplished, as before stated, through a step-by-step vertical movement of the auxiliary shaft or trip rod whereby a particular tens 95 level is reached and a step-by-step rotary movement of the auxiliary trip rod whereby a particular minor group, containing the line designated by the desired units digit, is reached.

100 Another feature resides in the provision of means whereby the movement of the selected brush into its operative position, and its return to normal, are both controlled by one magnet.

In the drawings, Figure 1 with Fig. 2 at the top, is a diagrammatic view of the mechanism and circuits of a switch embodying the features of this invention. More specifically, Fig. 1 shows in detail the operating mechanism, and Fig. 2 represents, with parts broken away, the sections of the contact banks with their individual brush sets, the brush selecting device and the auxiliary shaft coöperating with the brush shaft. Fig. 3 represents a portion of the driving rod showing the slots therein to coöperate with members of the mechanism proper. Fig. 4 is a partial sectional view on the line 10 4-4 in Fig. 1.

The switch herein disclosed is designed to serve five hundred lines, the terminals of which are arranged in sections of one hundred each, with a set of brushes coöperating 15 with each section. It will be obvious, however, that the capacity of this switch may be increased by making corresponding changes in the number of terminals served, in the number of brush sets, and in the mechanisms 20 auxiliary thereto.

Each individual switching apparatus comprises a brush shaft 1 slidably mounted in guide members upon a suitable frame (not shown). Upon this brush shaft is mounted 25 a plurality of brush carriers 2, each brush carrier having rigidly but insulatively secured thereto, a set of brushes 3, each set individual to a section 4 of the terminal bank, and normally maintained in an inoperative 30 position at the top of the corresponding section. The brush sets are adapted to be placed in operative relation therewith upon the actuation of a vertically and rotatably movable trip shaft 5, mounted parallel to 35 the brush shaft 1. The trip shaft 5 is provided with trip fingers 13 arranged at progressively increasing distances above the normal positions of their respective trip lugs 14 on the brush sets, and is normally 40 held in an inoperative position, as shown. The brush sets and the tripping devices associated therewith may be of substantially the same character as disclosed in United 45 States patent to Craft and Reynolds, No. 50 1,123,696. Trip shaft 5, however, is arranged to be operated to select a certain brush set upon its step-by-step downward movement in response to the first set of impulses representing the hundreds digit. For 55 this purpose, trip shaft 5 is rotatably mounted at the outer extremity of arm 17 integral with the ratchet rack 15, which is slidably and rotatably mounted on an auxiliary shaft 6 and is adapted to be operated by escape- 60 ment member 16 in response to the first series of impulses.

To further facilitate the selection of the desired line terminals, an auxiliary shaft 6 is provided, upon which is mounted a plurality 65 of radially-extending arms 7, ar-

ranged spirally about the shaft at uniform distances equivalent each to the space of ten contacts in the terminal bank. Shaft 6 is rotatably and slidably mounted parallel to the brush shaft 1, and is arranged by means 70 of the ratchet rack 12, integral therewith, and the escapement member 11 to be given a step-by-step downward movement in response to the second series of impulses representing the tens digit, thereby positioning 75 the arms 7 at a level such that, upon the subsequent downward movement of the brush shaft 1 and the engagement of the stop 8 thereon with any one of the arms 7, the previously selected brush set will be 80 halted at a level corresponding to the desired tens digit.

The arms 7, when positioned through the agency of ratchet rack 12, as described, represent levels corresponding to the same tens 85 digit, each arm and level represented thereby corresponding to a different units digit. Integral with the shaft 6 is the rotary ratchet 9, which, operated by the pawl 10 in response to the units impulses, rotates shaft 90 6 step-by-step to position an arm 7 in operative relation to stop 8 on the brush shaft, thereby selecting a level to correspond with the units digit.

Brush shaft 1, upon the engagement of 95 stop 8 with the selected arm 7, is thereby halted at a tens digit level corresponding with the units digit.

Means are provided for causing the downward movement of the brush shaft, consisting of a pulley 18 mounted upon the constantly rotating shaft 19, and an electromagnetically operated idler pulley 20 positioned on the opposite side of the rod 21, which is attached to the brush shaft 1 by means to be 100 hereinafter described. Similar means, comprising a pulley 22 mounted upon a shaft 23, constantly rotating but in an opposite direction with respect to that of shaft 19, and an idler 24 operated by the same electro- 105 magnet, are provided to facilitate the upward movement or return to normal of the brush shaft 1 and its coöperating members. Brush shaft 1 is given either a downward or upward movement, according as the idler 110 pulley 20 or the idler 24 is actuated, whereby rod 21 is forced into and held in frictional contact with the respective constantly rotating pulley.

Means are provided whereby only one 115 stepping magnet causes the successive step-by-step movements of the auxiliary selecting mechanism, the proper sequence of the execution thereof being determined by a bar 41 having cam surfaces thereon, and controlled by a slow magnet 49.

The armature 31 of the stepping magnet 28 is of the form of a bell-crank lever pivotally mounted on the pin 32 secured in the frame (not shown), and is held normally 130

against pin 33 by the coiled spring 34. At the lower extremity of bell-crank lever 31 are mounted pivotally the hook levers 35 and 36 adapted to coöperate respectively with the escapement members 16 and 11, and the pawl 10 adapted to engage with the rotary ratchet 9. Magnet 49 controls the bar 41 by means of the pawl 46, pivotally mounted at the extremity of the armature 48, which is normally held by spring 50 in the position shown. The bar 41 is directed in its movement by the pins 39 and 40 which coöperate with the slots 37 and 38 respectively. Bar 41 has, on its one side, cam surfaces with which the tail-pieces of the hook levers 35, 36 and 43 and the pawl 10 coöperate, and on its opposite face is provided with two sets of ratchet teeth 44 and 45 arranged to engage respectively with the operating pawl 46 of the armature of magnet 49, and with the retaining pawl 47 pivotally mounted on the pin 51 in the frame (not shown).

By means of slidable bar 41 and the cam surface thereon, magnet 49 determines the proper sequence of the operation of the escapement members 16 and 11 and the pawl 10, thereby controlling in corresponding order the stepping downward of the trip shaft 5, the downward movement of the auxiliary shaft 6, and the final rotative movement of the latter in response to the three sets of selective impulses respectively.

The further details of the controlling mechanism will be best understood, and the features of the invention best appear, from the description of the operation of such a switching device in selecting a desired set of line terminals.

Let it be assumed that it is desired to make connection with line No. 432. The controlling impulses from the substation sender will be transmitted over the conductor 25 to the stepping relay 26. It should be noted at this point that the standard substation impulser is arranged in series with the transmitter circuit and that it normally maintains a closed circuit through which talking current may flow. When, however, the impulser is manipulated, impulses are produced by the quick opening and closing of the pair of contacts of this device. In the well-known manner then a circuit is established when the substation receiver is removed from its hook, which circuit may be traced in this case from ground, battery, the winding of relay 26, the conductor 25 and thence through the circuit (not shown) which includes one side of the subscriber's line, the substation apparatus, back through the other side of the line to ground. Upon the consequent energization of relay 26, a circuit is closed for slow relay 27 which thereupon attracts its armature. Suppose, now, that the substation impulser is manipulated to transmit a series of four impulses.

Relay 26 will respond to each impulse, but relay 27, being slow to release, will hold up its armature. At its armature and back contact, relay 26 at each retraction closes a circuit for stepping magnet 28 extending from ground, battery, armature and back contact of relay 26, conductor 29, magnet 28, conductor 30, front contact and armature of slow relay 27, to ground. Magnet 28, responding to the impulses, intermittently closes at contacts 52 the circuit for slow magnet 49, which attracts and holds its armature 48 to position pawl 46 in engagement with the first tooth of rack 44.

In the normal position of bar 41 hook lever 35 engages in its cup-shaped extremity the escapement member 16, and armature 31, in response to the first set of impulses, operates through the medium of hook lever 35 the escapement member 16 four times, allowing thereby the ratchet hub 15 and the arm 17 integral therewith to be lowered four steps. Trip rod 5, being mounted on arm 17, is accordingly given a downward movement of four steps to position a trip finger 13' in operative relation with the trip lug 14' of the brush set serving the section of the terminal bank containing the desired set of terminals.

At the end of the first series of impulses, armature 31 of the stepping magnet returns to normal under action of spring 34, and permanently breaks the circuit for magnet 49. Magnet 49 thereupon deenergizes, allowing its armature 48 to be retracted by spring 50. Armature 48 in retracting carries the bar 41 down one step by virtue of the engagement of pawl 46 with the lowermost tooth of the rack 44.

Upon the first downward step of bar 41, retaining pawl 47 enters into engagement with the lowermost tooth of rack 45, and holds bar 41 in that position. Simultaneously, the one arm of hook lever 35 rides up on the elevated portion 54 of the cam surface of bar 41, and is thereby disengaged from escapement 16. At the same time hook lever 36 rides into the recess 55, thereby engaging at its cup-shaped extremity the escapement member 11.

The second series of impulses operates the stepping magnet 28, its armature again intermittently closing the circuit for slow magnet 49. Slow magnet 49 again pulls up its armature and places pawl 46 in operative engagement with the second tooth of the rack 44. The armature 31 of the stepping magnet 28 operates the escapement member 11, which is associated with the rack 12, three times, thereby dropping the auxiliary shaft 6 three steps to position the arms 7 thereon at a level corresponding to the digit 3.

Upon the first downward step of the auxiliary shaft 6, the collar 58, which is rigidly secured to shaft 6 and normally prevents the

movement of lever 56 suitably pivoted on pin 57, comes out of engagement with the extremity of lever 56. Lever 56 thereupon, under the action of spring 59, is momentarily 5 rotated in a clockwise direction, and by means of the connecting link 60, in slidable and rotative engagement with the crank-shaped portion 61 of trip shaft 5, rotates trip shaft 5, causing the operative engagement 10 of trip finger 13' of the shaft 5 with the controlling trip lug 14' of the previously selected brush set. The brushes are thereupon released in a manner, as described in the aforementioned patent, to assume an operative position with respect to the line terminals in the row served by the switching device.

At the termination of the second set of impulses, the circuit for slow magnet 49 is again interrupted at contacts 52, and magnet 49 retracts its armature which, under the action of spring 50, causes the second step downward of bar 41. Pawl 47 thereupon engages the second tooth of the rack 45 and retains bar 41 in its second position. Upon this second downward movement of bar 41, hook lever 36 rides up on the raised portion 62 of the cam surface of bar 41, thereby disengaging from the escapement member 11. Pawl 10, pivotally mounted on the armature 31, as shown in Fig. 4, is normally withheld out of operative relation with the rotary ratchet 9 by the engagement of the stud 85 with the cam surface 62 of bar 41, but upon 35 the second downward step of bar 41, stud 85, under the action of spring 87, rides into the recessed section 86 and allows the engagement of pawl 10 with the rotary ratchet 9.

Simultaneously, the one extremity of bell-crank lever 43, pivotally mounted at 63, rides up on the raised portion 64 of the surface of bar 41, and thereby causes at its other extremity the partial clockwise rotation of lever 66 pivotally mounted on the pin 67 in 45 the extended portion of lever 68. At its outer extremity, lever 66 in its rotative movement about the pin 67 causes the engagement of catch 75 with the pin 74 on the link 70, and at the same time through the medium of 50 the collar 77 on link 76, slidably arranged in engagement with bar 78 and connected therewith by spring 114, causes the downward movement of bar 78 pivotally mounted at 79 in the upper end of lever 72, to cause thereby 55 the disengagement of bar 78 from the lower extremity of lever 68. Lever 68, which constitutes the armature of the magnet 80, is thereby freed to allow its free movement about pin 69. Bell-crank lever 43 upon its 60 actuation closes the contacts 82, and link rod 76 at its lower extremity closes the contacts 83, both sets of contacts being in the circuit of magnet 80.

The third set of impulses representing the 65 digit 2 will now cause the operation of the

armature 31 of the stepping magnet 28 a corresponding number of times, whereby auxiliary shaft 6 is rotated two successive steps through the medium of pawl 10 previously placed in engagement with ratchet 9, positioning an arm 88 in operative position with respect to stop 8 on the brush shaft 1.

Slow magnet 49 pulls up and holds its armature during this set of impulses, its armature 48 positioning pawl 46 in operative 75 relation with the uppermost tooth of the rack 44. Simultaneously, armature 48 closes at the contacts 89 the following circuit for power magnet 80: ground, battery, magnet 80, conductor 90, contacts 83 previously closed by rod 76, conductor 91, contacts 82 previously closed by bell-crank lever 43, conductor 92, through contacts 89 to ground. Magnet 80 is thereupon energized and attracts its armature 68, which, being pivoted at 69, and held in rigid relation with the arm 70 through the lever 66, its projection 75 and the pin 74, brings rod 21 in operative engagement with the rotating pulley 19, clamping the rod between the idler pulley 20 and the pulley 19 to cause the downward movement of the brush shaft 1. Rod 21 is held in its normal position by the engagement of pawl 93 pivotally mounted at 81 with the slot 94 in the rod 21. Upon energization of magnet 95 80, however, pawl 93 is forced out of engagement with rod 21 by the movement of lever 70 toward the rod 21.

Brush shaft 1 is held in its normal position by the engagement of hook lever 95, 100 which is pivotally mounted on the block 97 with the catch 98 rigidly secured to the frame (not shown). Rod 21 has at its upper extremity and rigidly secured thereto a block 99, which slidably engages brush shaft 1, 105 its movement being limited by the block 97 and collar 100 on shaft 1. Block 99 upon the downward movement of rod 21 engages at its horizontal projection the lower extremity of lever 95, causing thereby the disengagement 110 thereof from the catch 98 and freeing shaft 1 from the supporting catch 98. Upon further downward movement of rod 21, block 99 engages collar 100 and causes the downward movement of shaft 1 with the rod 21. The 115 lower inwardly bent portion of lever 115, upon its movement toward the brush shaft 1 under action of spring 117, prevents the return of rod 21 with block 99 at its uppermost position directly underneath the 120 block 97.

Upon the termination of the last set of impulses, slow magnet 49 retracts its armature, allowing spring 50 through the medium of armature 48 and pawl 46 to step bar 41 to its third position, where it is held by retaining pawl 47. Simultaneously, armature 48 opens the contacts 89. The circuit for the power magnet 80 is maintained closed, however, at contacts 101, which are closed upon 125 130

the actuation of the armature 68 of magnet 80. The downward driving of shaft 1 is therefore continued until the projection 8 on the brush shaft 1 comes in contact with the stop 88 on the auxiliary shaft 6. Shaft 6 is thereupon momentarily forced downward, the downward movement thereof being communicated to the lever 102 pivoted at 106, through the medium of the escape-
 5 member 11, which is mounted at 103 thereon. Lever 102 is normally held in the position shown against the pin 104 by the spring 105, but, upon the momentary downward movement of member 11, is given a
 10 momentary rotation about pin 106, whereby the rod 107 connected to the lever 102 at its farther extremity by pin 108 is likewise given a downward movement. The downward movement of rod 107 causes the en-
 15 gagement of the collar 109, which is fixed on the rod 107, with the lever 66 with which rod 109 is in slidable engagement. Lever 66 is thereupon given a momentary counter-clockwise rotation about pin 67, causing the
 20 disengagement of catch 75 from pin 74. The rigidity of the three-bar linkage composed of levers 68, 66 and 70 is thereby destroyed and link 70 with the idler pulley 20 mounted at its extremity is allowed to retract, and
 25 the disengagement of the rod 21 from the driving pulley 18 is thereby accomplished. The actuation of lever 66 simultaneously causes the upward movement of the rod 76, whereby the circuit for magnet 80 is inter-
 30 rupted at the contacts 83, the armature 68 upon retraction again engaging the bar 78. Brush shaft 1 thereupon comes to a stop, the tripped brush set being positioned in opera-
 35 tive engagement with the terminals of the
 40 desired line 432.

The selection of the desired line in the above manner is made feasible by the arrangement of the terminals in the row served by the switch. The terminals are arranged in sections of one hundred each, the first one hundred being in the uppermost section. The selection of the fourth brush set from the top thereby selects the corresponding hundred. Each section of
 45 one hundred terminals is furthermore divided into ten groups of ten each, each group containing terminals of the same units digit, the uppermost group containing the terminals of the lines of the units digit 1.
 50 Like levels in these groups of ten contain terminals of the same tens digit, the uppermost terminal in each group of ten being of the tens digit 1, the next terminal down in each group being of the tens digit 2, etc.
 55 Accordingly, the step-by-step downward movement of auxiliary shaft 6 in response to the digit 3 determines the level of the arms 7 to correspond to the digit 3, thereby selecting simultaneously all the levels in the
 60 section of the fourth one hundred corre-

sponding with digit 3. The following ro-
 65 tative movement of shaft 6 two steps, in re-
 sponse to the impulses representing the
 units digit 2, causes the selection of an arm
 70 88 corresponding to the units digit 2, which
 arm has been previously positioned at the
 level of the tens digit 3.

As long as the calling line is in use, relay
 75 26 will be energized, and will hold the cir-
 70 circuit for slow relay 27 closed at its front con-
 tact. As soon, however, as the line circuit
 75 is interrupted upon the termination of the
 call, relay 26 de-energizes and causes, in turn,
 80 the de-energization of relay 27. Relay 27
 85 thereupon closes at its back contact a cir-
 80 circuit for magnet 80 as follows: ground, bat-
 85 tery, magnet 80, conductor 90, contacts 110,
 conductor 111, contacts 112 closed upon the
 90 first downward step of trip rod 5, conductor
 95 113, back contact and armature of relay 27,
 100 to ground. Magnet 80 upon attracting its
 105 armature 68, now in engagement with the
 105 bar 78, causes the application of the rod 21
 110 to the updrive pulley 22 through the me-
 dium of idler 24, mounted upon the extrem-
 115 ity of lever 72, which is swung about its
 115 pivot 73 in a counter-clockwise direction.
 Rod 21 immediately begins its upward
 120 movement, the block 99 at its upper end
 moving upwardly therewith until it en-
 125 gages the lower and inwardly bent portion
 130 of lever 115 held adjacent to the shaft 1 by
 135 spring 117, thereby carrying shaft 1 with it.
 The upward movement of the brush shaft 1
 140 ceases upon the engagement of the hori-
 145 zontal arm of lever 115 with the stop 118 rigid
 150 with the frame, whereby the lower end of
 155 lever 115 is thrown outwardly, disengaging
 160 from block 99. Simultaneously the hooked
 165 extremity of lever 95 engages the catch 98,
 170 also rigid with the frame, whereby brush
 175 shaft 1 is held in its normal position with
 180 the brush sets in inoperative position imme-
 185 diately above their respective sections of
 190 contacts.

At this point in the movement of rod 21,
 195 pawl 119 pivotally mounted on the arm 121,
 200 rotatably but not slidably secured by the
 205 collar 71 to the auxiliary shaft 6, engages
 210 slot 120, and pawl 122 pivotally mounted on
 215 the arm 17 extending from the ratchet 15,
 220 engages the slot 123 in the rod 21, whereby
 225 the auxiliary shaft 6 and the ratchet hub 15,
 230 together with the trip shaft 5, respectively
 235 are returned to normal position. The rod
 240 21 restores these members after brush shaft
 245 1 has reached, and is held in, its normal posi-
 250 tion, the restoration of these members tak-
 255 ing place during the movement of rod 21
 260 from the point of the disengagement of lever
 265 115 from block 99 upwardly till the rod 21
 270 is withdrawn from the drive pulley 22, this
 275 movement being allowed by the distance
 280 from the inwardly bent portion of lever 115
 285 to block 97 on shaft 1, equivalent to the
 290 130

space of ten contacts and sufficient to restore auxiliary shaft 6 and trip shaft 5 to normal. Auxiliary shaft 6 upon reaching its uppermost position is rotated back to its normal position by spring 133 incased in 134, the retaining pawl 132 riding up on the cylindrical portion of ratchet 9 and out of engagement therewith.

Upon shaft 6 having reached its uppermost position, collar 58 on shaft 6 engages with the tail piece of 56 to return trip shaft 5 with its associated trip fingers 13 to the normal position thereof. Ratchet hub 15 upon reaching its normal position opens at the extremity of arm 17, at the contacts 112, the circuit previously traced for magnet 80, whereby, upon the retraction of armature 68, the disengagement of rod 21 from the driving pulley 22 takes place. Rod 21 drops back to allow the catch at the extremity of lever 93 to enter slot 94, the pawl 93 maintaining rod 21 in its elevated position. Simultaneously with the actuation of the lever 72 to cause the disengagement of the rod 21 from the driving pulley 22, the bar 78 engages the extremity of the bell-crank lever 124 pivoted to the frame at 125, and causes the actuation of lever 124 to give rod 126 pivotally connected thereto at pin 127 an upward movement. Rod 126 has integral therewith the two projections 128, 129, arranged to engage upon the upward movement of rod 126 with the arms 130, 131 of the pawls 46, 47, respectively, whereby pawls 46, 47 are forced out of association with the racks 44 and 45 respectively, allowing spring 42 to return bar 41 to its normal position, as shown.

Provision is further made to cause the return to normal of the switch should the calling subscriber abandon the call at any stage during the setting up of the connection. This is accomplished by effecting the closure of the circuit for the magnet 80 to apply rod 21 to the updrive pulley 22, the circuit being closed at the back contact and armature of slow relay 27, which deenergizes upon the deenergization of stepping relay 26.

Should the calling subscriber hang up his receiver during or after the sending of the first set of impulses, stepping relay 26 will deenergize, breaking the circuit of slow relay 27. Relay 27 then closes the following circuit for magnet 80: ground, battery, magnet 80, conductor 90, contacts 110 closed, conductor 111, contacts 112 closed by the downward stepping of the ratchet hub 15 and its associated trip rod 5, conductor 113, back contact and armature of relay 27, to ground. Magnet 80 is energized and applies rod 21 to drive pulley 22, the linkages still being in the normal position, as shown. The upward movement of rod 21 carries ratchet hub 15 and the trip shaft 5

back to normal through the engagement of pawl 122 with slot 123.

Should the abandonment of the call take place during the sending of the second set of impulses, that is, before bar 41 has made its second downward step, leaving the bars 66 and 78 in their normal position, as shown, magnet 27 similarly closes the previously traced circuit for magnet 80. The bar 21 in its upward movement returns the hub ratchet 15 with the trip bar 5 and the auxiliary shaft 6 by means of the pawls 122 and 119 respectively.

Should the subscriber abandon the call during the sending of the last set of impulses, during which the down-drive of the brush shaft will already have begun, the stop 8 on brush shaft 1 will come in contact with one of the arms 7 on the auxiliary shaft 6, depending upon the point in the series of impulses at which the abandonment takes place. The brush shaft will come to a stop, as previously described, the circuit for magnet 80 being broken at contacts 83 and armature 68 again engaging bar 78. The following circuit is then closed for magnet 80 at the armature and back contact of relay 27: ground, battery, magnet 80, conductor 90, contacts 110 now closed, conductor 111, contacts 112 closed, conductor 113, armature and back contact of relay 27, to ground; magnet 80 causing the restoration to normal to take place as already described.

What is claimed is:

1. In an automatic selective switch adapted to respond directly to substation impulses, a plurality of contact banks, a shaft, a plurality of brush sets secured to said shaft each individual to one of said contact banks, motive means for said shaft, a trip rod parallel to said shaft having trip fingers thereon, means operative in response to a first train of impulses to position said trip rod to selectively trip a brush set, a stop mechanism for said shaft comprising a second shaft having a plurality of radially extending arms thereon, means responsive to a second train of impulses for moving said second shaft, means responsive to a third train of impulses for rotating said second shaft to position said selected brush set in engagement with the selected terminals, and means for disengaging said motive means when said first shaft engages said stop mechanism.

2. In an automatic selective switch adapted to respond directly to substation impulses, a plurality of contact banks, a shaft, a plurality of brush sets secured to said shaft each individual to one of said contact banks, motive means for said shaft, a trip rod parallel to said shaft having trip fingers thereon, means operative in response

to a first train of impulses to position said trip rod to selectively trip a brush set, a stop mechanism for said shaft comprising a second shaft having a plurality of radially extending arms thereon, means responsive to a second train of impulses for moving said second shaft, means responsive to a third train of impulses for rotating said second shaft to position said selected brush set in engagement with the selected terminals, means for disengaging said motive means when said first shaft engages said stop mechanism and means operated upon the release of the switch to cause said motive means to restore said brush sets to normal position.

3. In an automatic selecting switch adapted to respond directly to substation impulses, comprising a plurality of contact banks, a shaft, a plurality of brush sets secured to said shaft each individual to one of said contact banks, a trip shaft operative in response to the first train of impulses to select a brush set, an auxiliary shaft having a plurality of radially extending arms, escapement means actuated by the first train of impulses for operating the trip shaft, escapement means actuated by the second train of impulses for axially moving said auxiliary shaft, escapement means actuated by the third train of impulses for rotating said auxiliary shaft, power driven means for moving the brush sets to the position predetermined by said auxiliary shaft, power driven means for returning said brush sets to normal position after release, and a common magnet for controlling the application of the power driven means.

4. In an automatic selecting switch adapted to respond directly to substation impulses, a plurality of contact banks, a shaft, a plurality of brush sets secured to said shaft each individual to one of said contact banks, motive means for said shaft, a trip rod parallel to said shaft, means responsive to impulses for operating said trip rod to select a brush set, a stop mechanism for said shaft, means responsive to impulses for operating said stop mechanism to predetermine the advance of said shaft to cause the said selected brush to engage the selected terminals, and means for disengaging said motive means when said shaft completes said predetermined advance.

5. In an automatic selecting switch adapted to respond directly to substation impulses, a plurality of contact banks, a shaft, a plurality of brush sets secured to said shaft each individual to one of said contact banks, motive means for said shaft, means

operative in response to a first train of impulses for selecting a brush set, a stop mechanism for said shaft comprising a second shaft, means responsive to a second train of impulses for axially moving said second shaft, means responsive to a third train of impulses for rotating said second shaft to determine the advance of said second shaft to position said selected brush in engagement with the selected terminals, and means for disengaging said motive means when said first shaft engages said stop mechanism.

6. In an automatic line selecting switch responsive directly to substation impulses, a plurality of contact banks of one hundred terminals each, each bank containing groups of ten terminals each, terminals of like levels in said groups having the same designation for the next to the last digit and all terminals in each of said groups having the same designation for the last digit, a shaft, a plurality of brush sets secured to said shaft each individual to one of said contact banks, motive means for said shaft, means operative in response to a first train of impulses for selecting a brush set, means responsive to a second train of impulses for determining the movement of the selected brush with respect to the level whose terminals have the same designation for the next to the last digit to correspond with the second train of impulses, and means responsive to a third train of impulses for determining the advance of said selected brush to the group containing the terminals having the same designation for the last digit to correspond to the third train of impulses.

7. In a panel type switch, a plurality of movable brushes, motive means for moving said brushes, means for determining the advance of said brushes, a single means operated to cause said motive means to move said brushes said predetermined advance, and upon the release of the switch to cause said motive means to return said brush to normal position.

8. In a panel type switch, movable brushes, means responsive to impulses for determining the movement of said brushes, motive means for moving said brushes, means operated to cause said motive means to move said brushes to the selected position, and upon the release of the switch to cause said motive means to return said brushes to normal position.

In witness whereof, I hereunto subscribe my name this 24th day of November, A. D. 1916.

FRANK A. LUNDQUIST.
